CURTAIN DOOR INSTALLATION SYSTEM

CROSS-REFERENCE TO RELATED APPLICATIONS

This application is a continuation-in-part of, and claims priority in, U.S. Non-Provisional patent application Ser. No. 12/847,886, filed Jul. 30, 2010, which claims priority in U.S. Provisional Patent Application No. 61/213,929, filed Jul. 30, 2009, the contents of which are hereby incorporated herein by reference in their entirety.

BACKGROUND OF THE INVENTION

The present disclosed technology relates generally to a rolled door installation device, and in particular a cradle for holding a rolled curtain door and a system for installing the door above an opening.

Curtain door systems for residential and commercial use provide a movable barrier to cover a window or opening in a wall. The door systems may be manufactured to cover windows or openings having a wide variety of widths and heights. Curtain door systems are used in a variety of applications such as preventing the spread of fire in occupied structures, providing security to protect windows and doorways, and to cover large openings in walls where the use of large paneled doors is cumbersome or impractical such as openings for the passage of vehicles.

A curtain door system generally includes a curtain door having a series of interlocking slats of metal or plastic that spans an opening. The curtain door mounts above an opening or window on mounting hardware, and during operation is guided into position by guide rails at the periphery of the opening. The mounting hardware may include a pipe or drum that rotates between two head plates, and from which the curtain door is suspended. The interlocking feature of the slats allows the curtain door to be rolled about the pipe or drum when opening or closing the curtain door. Manufacturers typically ship curtain doors with the curtain door wound about the pipe or drum, or connected to the mounting hardware and drive mechanism. However, installation of the curtain door may be performed after installation of the guide rails, pipe, mounting hardware, and drive mechanism.

Rolled curtain doors are often heavy and awkward to install. Conventional installation methods require suspending the rolled curtain door below the pipe using slings or ropes. Workers pull on the ropes to lift the door up to the pipe for attachment. Workers next ascend ladders and manually adjust the orientation of the rolled door to align the top slat with the pipe, and connect the two. The curtain door is then rolled off of the ropes and onto the pipe. As a result, the conventional tools and process used to install curtain doors is fraught with challenges, especially when installing doors that weigh hundreds of pounds, or used to cover large openings having great height or width. Moreover, the conventional installation process can lead to injury of the workers installing the door because of a need to use body strength and ladders to complete installation. Therefore, there is a need for a curtain door installation system that permits a worker to safely and accurately install a curtain door regardless of the height of the opening the door will cover, and the size and weight of the door.

Therefore, those who install curtain door systems desire an installation tool that provides an efficient and safe method for

installing these systems. The disclosed subject matter provides these features and advantages.

SUMMARY OF THE INVENTION

5

In accordance with the disclosed subject matter, a rolled curtain door may be supported by a cradle assembly having a plurality of roller assemblies configured to support the curtain door and permit rolling of the door thereon to aid in mounting the door above an opening. The roller assembly includes a plurality of tubular rollers within a frame forming a C-shaped supporting surface. The cradle assembly includes wheels depending therefrom allowing the cradle assembly to independently roll across a surface. The cradle assembly may be mounted on the tines of a fork on a lifting device, such as a forklift or lifting assembly, to raise the curtain door up to a mounting position on a wall above a door opening.

If desired, particular embodiments may optionally include a lift assembly attached to the cradle. The lift assembly includes a tower extendable by a piston and cylinder unit. The tower has a fork with tines projecting therefrom. The tower is attached to a base having casters for manually rolling the cradle and lift assembly around a worksite. Stabilizers on the base may be used to support and level the assembly when in use. A winch motor with a cable is attached to the tower and may be used to assist in loading a rolled curtain door onto the cradle. Optionally, a hoist attached to the tower may be used to load a rolled curtain door onto the cradle.

30

BRIEF DESCRIPTION OF THE DRAWINGS

The drawings constitute a part of this specification and include exemplary embodiments of the disclosed subject matter illustrating various objects and features thereof, wherein like references are generally numbered alike in the several views.

FIG. 1 is a rear perspective view of a first alternative embodiment curtain door installation system embodying principles of the disclosed subject matter where a cradle supporting a rolled curtain door is attached to, and elevated by, a lifting device.

FIG. 2 is a rear perspective view of the curtain door installation system embodying principles of the disclosed subject matter showing the cradle with extensions assemblies extended from a central assembly.

FIG. 3 is a front elevational view of the cradle attached to a lifting device.

FIG. 4 is a second alternative embodiment curtain door installation system including a cradle attached to a lift with an integrated hoist.

FIG. 5 is a rear perspective view of an alternative embodiment cradle.

FIG. 6 is a right elevation view of the first roller assembly.

FIG. 7 is a rear elevation view of the first roller assembly.

FIG. 8 is a plan view of the first roller assembly.

FIG. 9 is a rear perspective view of the first roller assembly.

DETAILED DESCRIPTION

60

As required, detailed aspects of the disclosed subject matter are disclosed herein; however, it is to be understood that the disclosed aspects are merely exemplary of the invention, which may be embodied in various forms. Therefore, specific structural and functional details disclosed herein are not to be interpreted as limiting, but merely as a basis for the claims and as a representative basis for teaching one skilled in the art how

to variously employ the present invention in virtually any appropriately detailed structure.

Certain terminology will be used in the following description for convenience in reference only and will not be limiting. Said terminology will include the words specifically mentioned, derivatives thereof and words of similar meaning.

Referring to the drawings in more detail, the reference numeral 101 generally designates a curtain door installation system embodying the principles of the disclosed subject matter. Referring to FIG. 2, the system 101 generally includes a cradle 102 having a central assembly 104, and first and second extension assemblies 152 and 154. By way of example, and not to be construed as limiting, the system 101 is shown in FIG. 1 attached to a lift assembly 202, and elevated, for installing the rolled curtain door 310 above an opening 302 in a wall 304. A rolled door system generally includes a curtain door 310 attached to a pipe or drum located between two head plates 306, a drive mechanism for raising and lowering the curtain door 310, and guide rails for keeping the curtain door 310 aligned with the opening during operation.

Referring to FIG. 2, cradle 102 generally comprises a central assembly 104, and first and second extension assemblies 152 and 154. Central assembly 104 includes a cross member 106 having a pair of fork sleeves 108 secured to the underside, and two roller assemblies 114 secured to the top. Cross member 106 may comprise a hollow steel tube with opposite open ends, and having a rectangular cross section for slidably receiving a leg 156 of first or second extension assemblies 152 and 154. Cross member 106 is the part that supports the roller assemblies 114, and for mounting first and second extension assemblies 152 and 154. Fork sleeves 108 comprise a steel tube having a rectangular cross section, and dimensioned to slidably receive the tines of a fork from a lifting device including, but not limited to, lift assembly 202, a forklift or a lift truck (not shown). Each fork sleeve 108 has an aperture 110 for receiving a locking member such as a locking pin or a set bolt 112 to secure cradle 102 to the fork of the lifting device. Alternatively, fork sleeves 108 may be welded to the fork.

Each roller assembly 114 includes an arm 116 mounting two rollers that are opposite each other and allow free rotation of the roller thereon. The roller may include, but is not limited to, a metal, plastic, or composite drum, wheel, or tube, preferably a wheel 120 having a rubber contact surface. Wheels 120 are mounted on arm 116 by a vertical support 115, wherein the rotational axis of wheel 120 is perpendicular to arm 116, and wheel 120 is spaced a sufficient distance apart as to cradle a rolled curtain door 310. Although a wheel 120 is shown and described, any suitable roller or rollers may be used with cradle 102 that permits free rotation of the rolled curtain door 310 thereon. Roller assemblies 114 are mounted with arm 116 perpendicular to cross member 106, thereby supporting rolled curtain door 310 parallel to cross member 106. The fork sleeves 108, cross member 106, vertical support 115, and roller assemblies 114 are secured by welding, or alternatively, by fasteners such as a nut and bolt combination.

Cradle 102 may suitably function with or without first and second extension assemblies 152 and 154. Extension assemblies 152 and 154 may be connected to central assembly 104 when supporting an especially wide or heavy curtain door 310. First extension assembly 152 includes leg 156 mounting roller assembly 114 at one end. Leg 156 comprises a solid or hollow steel tube having a rectangular cross section adapted for insertion into cross member 106. Roller assembly 114 may be secured to leg 156 by a pair of U-bolts 158, nuts 160, and a plate 162, or alternatively by welding.

Second extension assembly 154 is generally identical to first extension assembly 152 and therefore will not be described. Leg 156 end opposite roller assembly 114 is inserted into the open end of cross member 106 with roller assembly 114 facing up, and are slid in and out as needed to position first and second roller assemblies 114 under the rolled curtain door 310.

Cradle 102 may optionally be powered by a motor 276 that can rotate wheels 120 thereby rotating the rolled curtain door 310 thereon when mounting the curtain door 310 above an opening. Roller assemblies on cross member 106 may be connected by a shaft 174 having a driven sprocket 172. Driven sprocket 172 is connected to a drive sprocket 176 on motor 276 by a chain 178. Motor 276 is mounted on either lift assembly 202 or cross member 106, preferably lift assembly 202. Motor 276 may be an electrical motor powered by a suitable electrical power supply, or a hydraulic motor powered by a complimentary power source.

In use, cradle 102 is mated to a lifting device having a pair of forks projecting therefrom. The forks are inserted into fork sleeves 108, and cradle 102 is secured to the forks by tightening set bolts 112 in apertures 110. First and second extension assemblies 152 and 154 are adjusted or removed, as needed, to properly support a rolled curtain door 310. A curtain door 310 is then loaded onto cradle 102, and cradle 102 is then raised up to the proper height above an opening where the rolled curtain door 310 is attached to the installed door mounting hardware such as a pipe or drum. After the rolled curtain door 310 is attached to the mounting hardware, roller assemblies 114 allow free rotation of the curtain door 310 off of the cradle 102 as the curtain door 310 is rolled onto the pipe or drum, or motor 276 may be engaged to rotate wheels 120 to assist in transferring the rolled curtain door 310 to the door mounting hardware.

Occasionally a rolled curtain door 310 may already be attached to mounting hardware and a drive mechanism. Therefore, although a rolled curtain door 310 is described, cradle 102 may be used to install a rolled curtain door above a doorway when the rolled curtain door already has its mounting hardware installed using the same process described above.

Supporting the rolled curtain door 310 with cradle 102, and using roller assemblies 114 to transfer the curtain door 310 to the mounting hardware avoids the perils previously encountered when installing curtain doors. Namely, workers can avoid use of straps, step ladders, and body strength currently necessary to suspend and raise heavy curtain door below its mounting hardware. This provides workers with a tool to safely and accurately install a curtain door regardless of the height or location of the mounting hardware, and the size or weight of the door.

A curtain door installation system comprising a first alternative embodiment curtain door installation system 201 is shown in FIGS. 1 and 2, and includes a cradle 102 attached to lift assembly 202. Lift assembly generally comprises a tower 252 connected to a base 204. The generally rectangular base 204 includes a frame 206 constructed of tubular members having a rectangular cross section. Frame 206 comprises a rectangle having front and rear members 208 and 210, and interconnecting side members 212 and 214. The ends of front and rear members 208 and 210 are joined to their respective side members 212 and 214 in a conventional manner such as by welding. Base 204 is supported by casters 216 secured to frame 206 allowing lift assembly 202 to be rolled around a worksite by a worker.

A deck 218 is secured to frame 206 and provides a mounting surface for two deck ribs 220. Each deck rib 220 is located on top of deck 218 adjacent to a side member 212 and 214.

Ribs 220 comprise a solid or hollow steel tube having a rectangular cross section, and traverse deck 218 from front to back adding rigidity to base 204. The front and rear of each rib 220 provides a mounting surface for a stabilizer 222 used to bias against the surface supporting lift assembly 202, thereby stabilizing and holding lift assembly 202 when in use. Stabilizer 222 may be a conventional manually-operated stabilizer, or a mechanical stabilizer operated using electric or hydraulic power.

Tower 252 generally comprises an extendable mast 254 that raises and lowers a fork 266. Mast 254 is centered at the rear of base 204 and secured thereto by welding. Mast 254 is further secured to base 204 by a heel 256 that is secured to both deck 218 and mast 254 by welding, completing formation of a rigid box-like structure that adds further stability to the connection between base 204 and mast 254. Mast 254 is further stabilized by angular trusses 260 secured to mast 254 at one end, and base 204 at the other end by welding. A handle 262 on the rear of each truss 260 permits a worker to manually maneuver lift assembly 202. Mast 254 comprises interlocking rails supporting a carriage 264 and a forward-facing fork 266. Mast 254 functions in a similar manner as those found on a forklift truck for raising and lowering carriage 264 and fork 266.

Mast 254 is raised and lowered by a piston and cylinder unit (p-c unit) 268 connected at one end to base 204 and at another end to mast 254 by a chain. P-c unit 268 communicates with a reservoir 270 via a valve 272 and hose 274. P-c unit 268 may function using a pneumatic system or a hydraulic system, preferably a pneumatic system. Actuation of valve 272 to a first position extends p-c unit 268 and raises fork 266. Actuation of valve 272 to a second position ceases movement of p-c unit 268. Actuation of valve 272 to a third position withdraws p-c unit 268 and lowers fork 266.

A winch motor 226 winds-up and lets out a cable 228 having a hook 230 for connecting to a rolled curtain door 310. Cable 228 passes through a guide 232 keeping cable 228 aligned with winch motor 226 and a wheel 234 disposed at the top of the mast 254. Wheel 234 allows for cable 228 to roll on when lifting a rolled curtain door 310 onto cradle 102.

In use, curtain door installation system 201 provides for installation of a rolled curtain door 310 without the need of a forklift truck. Cradle 102 is attached to fork 266 of the lift assembly 202 in the same manner as described above. First and second extension assemblies 152 and 154 are adjusted or removed as needed depending on the size or weight of the rolled curtain door 310. After loading a rolled curtain door 310 onto cradle 102 using cable 228 and winch 226, lift assembly 202 may be freely rolled across a surface. Using handles 262, a worker can manually position lift assembly 202 and curtain door 310 below an opening to be covered. After engaging stabilizers 222 to immobilize and level lift assembly 202, a worker actuates valve 272 to the first position to raise fork 266 and cradle 102. When cradle 102 has reached the proper height to offload the rolled curtain door 310 to the mounting hardware, valve 272 is moved to the second position stopping movement of cradle 102. After the curtain door 310 is offloaded, valve 272 is moved to the third position permitting cradle 102 to be lowered to the ground.

A curtain door installation system comprising a second alternative embodiment curtain door installation system 401 is shown in FIG. 4, and includes cradle 102 and lift assembly 202 as described above, and further including hoist 402. Hoist 402 is attached to the top of tower 252 for assisting in loading a rolled curtain door 310 onto cradle 102. Hoist 402 generally includes a boom 404 that pivots atop tower 252, and a p-c unit 418 for raising and lowering boom 404. Boom 404 extends

forward from the rear of lift assembly 202 across the top of tower 252, terminating in front of lift assembly 202. Boom 404 may comprise a hollow steel tube having a rectangular cross section. Boom 404 pivots about a bracket 408 extending from the top of tower 252. P-c unit 418 attaches at one end to the rear of boom 404, and at another end to tower 252. P-c unit 418 may function in a similar manner, and use like components, as p-c unit 268 described above. A hook 406 at the forward end of boom 404 allows for connection of a chain 410. Straps 414 may be wrapped around the rolled curtain door 310 and connected to the free end of chain 410 by a cable 412. Optionally, electrically-powered lights 416 may be attached to tower 252 providing illumination of cradle 102 and workspace.

In use, the rolled curtain door 310 is connected to the hoist 402 as described above. Actuation of p-c unit lifts the rolled curtain door 310 off of the ground or a vehicle. Workers may then guide the rolled curtain door 310 over cradle 102 and lower boom 404 thereby placing the door 310 between wheels 120 of the cradle 102. Rolled curtain door 310 is then disconnected from hoist 402, and raised into position on cradle 102 for installation.

Referring to FIGS. 5-9 an alternative embodiment cradle assembly 502 is shown and described for installing rolled curtain doors, similar to the rolled curtain door 310 above. The cradle assembly 502 generally includes roller assemblies connected by a cross member 504. The cross member 504 may comprise a tubular member having a rectangular cross-section extending between a first end 506 and an opposite end. The cradle assembly 502 is shown with a first roller assembly 520a, a second roller assembly 520b, and a third roller assembly 520c mounted to the cross member 504. The first roller assembly 520a is mounted adjacent the first end 506, the second roller assembly 520b is mounted adjacent the second end, and the third roller assembly 520c is disposed between the first end 506 and the second end 508.

A receiver 510 is mounted to the cross member 504 for receiving the tines of a lifting fork on a lifting device. The receivers 510 are spaced apart to accept the tines of the lifting fork and are located along the cross member 504 so that the cradle assembly 502 is evenly balanced relative to the lifting device when the cradle assembly 502 is elevated. The receivers 510 may be apertures located within the cross member 504 or may be at the exterior of the cross member 504, and be similar in structure and function to the fork sleeve 108 above. As such, the receiver 510 is secured to the cross member 504 by suitable means including welding and may include an aperture for receiving a locking member, such as a locking pin or a set bolt to secure the cradle assembly 502 to the forks of the lifting device. The cross member 504 supports the roller assemblies 520a, 520b, and 520c when the cradle assembly 502 is mounted to the tines of a lifting device including the lift assembly 202 above, a forklift, or a lift truck.

Referring to FIGS. 6-9, the first roller assembly 520a extends between a front end 532a and a rear end 534a, and includes a plurality of rolling mechanisms 562 disposed within a frame 522a. The rolling mechanism 562 may include a plurality of wheels, or a tubular member 564 rotably mounted to a shaft 570 extending between a first end 566 and a second end 568. The frame 522a includes opposite spaced-apart first and second side members 524a, 538a. The first side member 524a includes an upper end 526a with an aperture for connecting a first end 566 of a rolling mechanism 562 thereto. The second side member 538a includes an upper end 540a with an aperture for connecting a second end 568 of a rolling mechanism 562 thereto. The ends of the shaft 570 may pass through the apertures and may be secured thereto by suitable

means, including welding, or alternatively the ends of the shaft 570 are threaded and secured to the side members by a threaded fastener 572 including a bolt. Each of the first and second side members 524a, 538a may include a plurality of apertures about the upper ends 526a, 540a for arranging rolling mechanisms 562 in an upwardly-open C-shaped configuration therebetween. In an embodiment rolling mechanisms are located at the lower portion of the upper ends 526a, 540a, and at the upper portion of the upper ends 526a, 540a. The rolling mechanisms 562 are mounted between the first side member 524a and second side member 538a whereby the tubular member 564 projects beyond the upper ends 526a, 540a for rollingly supporting a rolled curtain door 310. The first side member 524a includes a lower end 528a opposite the upper end 526a having a centrally located slot 530a for connecting the first side member 524a to the cross member 504. Additionally, the second side member 538a includes a lower end 542a opposite the upper end 540a having a centrally located slot (not shown) that minors the structure of slot 530a for connecting the second side member 538a to the cross member 504. In an embodiment the slots have a rectangular dimension for accommodating a rectangular cross member 504.

One or more connectors 552 extend between the side members 524a and 538a for maintaining the spaced relationship of the side members and for providing additional structural support to the frame 522a. The connector 552 may include a rod with first and second ends 556, 558 welded to the side members 524a and 538a, respectively, or a rod wherein the first and second ends 556, 558 are threaded and pass through apertures in the side members and may be secured thereto by a threaded fastener 554, including a nut. In an embodiment a connector 552 connects the corner of each side member 524a with the opposite corner of the second side member 538a.*

The first roller assembly 520a further includes a beam 512a connected to the cross member 504 and connected to and extending substantially the length of the interior face of the first side member 524a for providing additional structural support to the first roller assembly 520a. Wheels 580, including caster wheels, depend from the bottom of the first side member 524a at the front end 532a and rear end 534a for supporting the first roller assembly 520a on the ground when the cradle assembly 502 is not connected to a lifting device. The wheels 580 may rotate about a mounting plate 582 that is attached to the first side member 524 by suitable means, including welding, or a nut and bolt combination.

Referring to FIG. 5, the second roller assembly 520b extends between a front end 532b and a rear end 534b, and includes a plurality of rolling mechanisms 562 disposed within a frame 522b. The frame 522b includes opposite spaced-apart first and second side members 524b, 538b. The first side member 524b includes an upper end 526b with an aperture for connecting a first end 566 of a rolling mechanism 562 thereto. The third side member 538b includes an upper end 540b with an aperture for connecting a second end 568 of a rolling mechanism 562 thereto. The ends of the shaft 570 may pass through the apertures and may be secured thereto by suitable means, including welding, or alternatively the ends of the shaft 570 are threaded and secured to the side members by a threaded fastener 572 including a bolt. Each of the first and second side members 524b, 538b may include a plurality of apertures about the upper ends 526b, 540b for arranging rolling mechanisms 562 in an upwardly-open C-shaped configuration therebetween. In an embodiment rolling mechanisms are located at the lower portion of the upper ends 526b, 540b, and at the upper portion of the upper ends 526b, 540b. The rolling mechanisms 562 are mounted between the first side member

side member 524b and second side member 538b whereby the tubular member 564 projects beyond the upper ends 526b, 540b for rollingly supporting a rolled curtain door 310. The first side member 524b includes a lower end 528b opposite the upper end 526b having a centrally located slot 530b for connecting the first side member 524b to the cross member 504. Additionally, the second side member 538b includes a lower end 542b opposite the upper end 540b having a centrally located slot (not shown) that minors the structure of slot 530b for connecting the second side member 538b to the cross member 504. In an embodiment the slots have a rectangular dimension for accommodating a rectangular cross member 504.

One or more connectors 552 extend between the side members 524b and 538b for maintaining the spaced relationship of the side members and for providing additional structural support to the frame 522b. The connector 552 may include a rod with first and second ends 556, 558 welded to the side members 524b and 538b, respectively, or a rod wherein the first and second ends 556, 558 are threaded and pass through apertures in the side members and may be secured thereto, by a threaded fastener 554, including a nut. In an embodiment a connector 552 connects each corner of the first side member 524b with the opposite corner of the second side member 538b.

The second roller assembly 520b further includes a beam 512b connected to the cross member 504 and connected to and extending substantially the length of the interior face of the second side member 538b for providing additional structural support to the third roller assembly 520b. The third roller assembly 520b includes a wheel 580 depending from the second side member 538b at the rear end 534b and at the front end 532b for supporting the second roller assembly 520b on the ground when the cradle assembly 502 is not connected to a lifting device.

Referring to FIG. 5, the third roller assembly 520c extends between a front end 532c and a rear end 534c, and includes a plurality of rolling mechanisms 562 disposed within a frame 522c. The frame 522c includes opposite spaced-apart first and second side members 524c, 538c. The first side member 524c includes an upper end 526c with an aperture for connecting a first end 566 of a rolling mechanism 562 thereto. The second side member 538c includes an upper end 540c with an aperture for connecting a second end 568 of a rolling mechanism 562 thereto. The ends of the shaft 570 may pass through the apertures and may be secured thereto by suitable means, including welding, or alternatively the ends of the shaft 570 are threaded and secured to the side members by a threaded fastener 572 including a bolt. Each of the first and second side members 524c, 538c may include a plurality of apertures about the upper ends 526c, 540c for arranging rolling mechanisms 562 in an upwardly-open C-shaped configuration therebetween. In an embodiment rolling mechanisms are located at the lower portion of the upper ends 526c, 540c, and at the upper portion of the upper ends 526c, 540c. The rolling mechanisms 562 are mounted between the first side member 524c and second side member 538c whereby the tubular member 564 projects beyond the upper ends 526c, 540c for rollingly supporting a rolled curtain door 310. The first side member 524c includes a lower end 528c opposite the upper end 526c having a centrally located slot 530c for connecting the first side member 524c to the cross member 504. Additionally, the second side member 538c includes a lower end 542c opposite the upper end 540c having a centrally located slot (not shown) that minors the structure of slot 530c for connecting the second side member 538c to the cross member 504. In an embodiment the slots have a rectangular dimension for accommodating a rectangular cross member 504.

One or more connectors 552 extend between the side members 524c and 538c for maintaining the spaced relationship of the side members and for providing additional structural support to the frame 522c. The connector 552 may include a rod with first and second ends 556, 558 welded to the side members 524c and 538c, respectively, or a rod wherein the first and second ends 556, 558 are threaded and pass through the apertures in the side members and may be secured thereto by a threaded fastener 554, including a nut. In an embodiment a connector 552 connects each corner of the first side member 524c with the opposite corner of the second side member 538c.

The third roller assembly 520c includes a wheel 580 depending from the first side member 524c at the rear end 534c, and a wheel 580 depending from the second side member 538c at the front end 532c for supporting the third roller assembly 520c on the ground when the cradle assembly 502 is not connected to a lifting device.

The wheels 580 depending from the cradle assembly 502 allow the cradle assembly 502 to be rolled moved across a surface when the cradle assembly 502 is not connected to a lifting device.

In use, the cradle assembly 502 is mated to a lifting device having a pair of forks projecting therefrom. A curtain door 310 is loaded onto the cradle assembly 502 with the first roller assembly 520a, second roller assembly 520b, and third roller assembly 520c supporting the curtain door 310 parallel to the cross member 504. The cradle assembly 502 may be rolled along a surface to position the cradle assembly 502 in a position to be mated to a lifting device. The forks are inserted into the receivers 510, and the cradle assembly 502 is then elevated to the proper height above an opening where the rolled curtain door 310 is installed. Roller assemblies 520a, 520b, and 520c allow free rotation of the curtain door 310 off of the cradle assembly 502 as the door is installed.

The cradle assembly 502 may be used to remove a rolled curtain door installed above an opening by elevating an empty cradle assembly 502 beneath the installed curtain door and rolling the door on to the roller assemblies 520.

It will be appreciated that the components of cradles 102 and 502, and installation systems 101, 201, and 401 may be used for various other applications. Moreover, cradles 102 and 502, and installation systems 101, 201, and 401 may be fabricated in various sizes and from a wide range of suitable materials, using various manufacturing and fabrication techniques.

It is to be understood that while certain aspects of the disclosed subject matter have been shown and described, the disclosed subject matter is not limited thereto and encompasses various other embodiments and aspects.

Having thus described the disclosed subject matter, what is claimed as new and desired to be secured by Letters Patent is:

1. A cradle for supporting a rolled curtain door, comprising:

a cross member extending between a first end and a second end;

a first and a second roller assembly, each roller assembly, comprising:

(a) a frame, comprising:

(1) a first side member extending between an upper end and a lower end, wherein the lower end is connected to the cross member, and the upper end extends away from the lower end; and

(2) a second side member extending between an upper end and a lower end, the second side member disposed opposite to and spaced apart from the first side member, and wherein the lower end is con-

nected to the cross member, and the upper end extends upward and away from the lower end; and

(b) a plurality of rolling mechanisms disposed between the first side member and second side member arranged in an upwardly-open C-shaped configuration for rollingly supporting a rolled curtain door; and wherein the first roller assembly is connected adjacent the cross member first end; and the second roller assembly is connected adjacent the cross member second end.

2. The cradle of claim 1, wherein:

the first side member extends between a front end and a rear end, and the upper end forms an upwardly-open C-shaped edge;

the second side member extends between a front end and a rear end, and the upper end forms an upwardly-open C-shaped edge;

a first connector extends between the first side member front end, and the second side member front end; and a second connector extends between the first side member rear end, and the second side member rear end.

3. The cradle of claim 2, further comprising:

a first slot centrally located within the lower end of the first side member for connecting the first side member to the cross member; and

a second slot centrally located within the lower end of the second side member for connecting the second side member to the cross member.

4. The cradle of claim 3, further comprising:

a first beam connecting the first side member of the first roller assembly to the cross member; and

a second beam connecting the second side member of the second roller assembly to the cross member.

5. The cradle of claim 1, further comprising a third roller

assembly connected to the cross member, wherein the third roller assembly is disposed between the first roller assembly and the second roller assembly.

6. The cradle of claim 1, further comprising a wheel depending from the roller assembly for supporting the cradle on a surface.

7. The cradle of claim 1, further comprising:

a first receiver connected to the cross member for receiving a tine of a lifting fork; and

a second receiver connected to the cross member and spaced apart from the first receiver for receiving a tine of a lifting fork.

8. The cradle of claim 1, wherein the rolling mechanism comprises:

a shaft; and

a tubular member rotatably mounted to the shaft.

9. A cradle for supporting a rolled curtain door, comprising:

a cross member extending between a first end and a second end;

a roller assembly, comprising:

(a) frame, comprising:

(i) a first side member extending between a front end and a rear end, and an upper end and a lower end, wherein the lower end is connected to the cross member, and the upper end extends away from the lower end forming an upwardly-open C-shaped edge;

(ii) a second side member extending between a front end and a rear end, and an upper end and a lower end, the second side member disposed opposite to and spaced apart from the first side member, and wherein the lower end is connected to the cross

11

- member, and the upper end extends upward and away from the lower end forming an upwardly-open C-shaped edge;
- (b) a plurality of rolling mechanisms extending between a first end and a second end, wherein the first end is connected to the first side member upper end and the second end is connected to the second side member upper end, wherein the rolling mechanisms are arranged adjacent the upwardly-open C-shaped edge forming an upwardly-open support for rollingly supporting a rolled curtain door;
- a first receiver connected to the cross member adjacent the first side member; and
- a second receiver connected to the cross member adjacent the second side member.
- 10.** The cradle of claim 9, further comprising:
- a first connector extending between the first side member rear end and the second side member front end; and
- a second connector extending between the first side member front end and the second side member rear end.
- 11.** The cradle of claim 10, further comprising a plurality of wheels depending from the bottom end of the first side member and second side member.

12. The cradle of claim 9, wherein the rolling mechanism comprises:

- a shaft; and
- a tubular member rotatably mounted to the shaft.
- 13.** A cradle for supporting a rolled curtain door, comprising:
- a cross member extending between a first end and a second end;
- a roller assembly, comprising:
- (a) a frame, comprising:
- (i) a first side member extending between a front end and a rear end, and a lower end and an upper end, wherein the upper end forms an upwardly-open C-shaped edge;
- (ii) a first slot centrally located within the lower end of the first side member for connecting the first side member to the cross member;
- (iii) a second side member disposed opposite the first side member and extending between a front end and a rear end, and a lower end and an upper end, wherein the upper end forms an upwardly-open C-shaped edge;

12

- (iv) a second slot centrally located within the lower end of the second side member for connecting the second side member to the cross member; and
- (v) a connector extending between the first side member and the second side member;
- (b) a plurality of rolling mechanisms disposed between the first side member and the second side member adjacent the upwardly-open C-shaped edge for rollingly supporting a rolled curtain door, the rolling mechanism comprising:
- (i) a shaft extending between a first end and a second end, wherein the first end is connected to the first side member and the second end is connected to the second side member; and
- (ii) a tubular member rotatably mounted to the shaft; wherein a first roller assembly is connected adjacent the cross member first end, a second roller assembly is connected adjacent the cross member second end, and a third roller assembly is connected to the cross member between the first roller assembly and the second roller assembly;
- a first receiver connected to the cross member; and
- a second receiver connected to the cross member and spaced apart from the first receiver.
- 14.** The cradle of claim 13, further comprising:
- a first beam connecting the first side member of the first roller assembly to the cross member; and
- a second beam connecting the second side member of the second roller assembly to the cross member.
- 15.** The cradle of claim 13, further comprising:
- a first wheel depending from the front of the bottom end of the first side member of the first roller assembly;
- a second wheel depending from the rear of the bottom end of the first side member of the first roller assembly;
- a third wheel depending from the front of the bottom end of the second side member of the second roller assembly;
- a fourth wheel depending from the rear of the bottom end of the second side member of the second roller assembly;
- a fifth wheel depending from the bottom end of the first side member of the third roller assembly; a sixth wheel depending from the bottom end of the second side member of the third roller assembly.
